CARRIER FOR A BEVERAGE CONTAINER OR THE LIKE

Richard H. Van Den Berg, Glendale, Wis., assignor to
Dimensional Products, Inc., Milwaukee, Wis.

Filed Mar. 15, 1971, Ser. No. 124,650

Term of patent 14 years

Int. Cl. D3—02

U.S. Cl. D87—1 R

FIG. 1 is a perspective view of a carrier for a beverage container or the like, showing my new design;

FIG. 2 is a fragmentary elevational view;

FIG. 3 is an elevational view looking from the right of FIG. 2;

FIG. 4 is an elevational view showing the side opposite that seen in FIG. 2;

FIG. 5 is an elevational view looking from the left of FIG. 2;

FIG. 6 is a top plan view thereof; and

FIG. 7 is a bottom plan view thereof.

I claim:

The ornamental design for a carrier for a beverage container or the like, as shown.
